UNITED STATES PATENT OFFICE

2,436,431

TELEPHONE TERMINAL

Walter C. Hasselhorn, Chicago, Ill., assignor to
 Cook Electric Company, Chicago, Ill., a corporation of Illinois

Application June 21, 1943, Serial No. 491,615

5 Claims. (Cl. 173—330)

1

This invention is directed to a simple, efficient and inexpensive form of telephone pole jack, and more particularly to a device of this type that may be advantageously used as a compact and weatherproof portable telephone patrol station.

The principal objects of the invention are to provide a telephone patrol station that is compact and durable; to provide improved means in a telephone patrol station construction and particularly in the framework of the housing thereof; to utilize this improved means for the purpose of securing a portable weatherproof unit and of securing an extremely inexpensive and simple structure; and to provide improved means for securing greater adaptability of a device having these improved characteristics.

The telephone patrol station herein disclosed is adaptable to a wide variety of uses and uniquely to communication systems set up along docks, firing ranges, warehouses, highway patrols, forestry and national park services, airfields, munitions and loading plants and wherever coastal protection may be desirable. The simplicity of the structure, its inexpensive construction and its durability against the elements of weather make it particularly useful for a broad field of application and assures service at all times.

The invention is also directed to an improved closure device for the jack opening, which closure is designed to maintain the opening covered as long as the jack is not inserted, but to swing to open position by the mere insertion of the jack so as to require the attendant to use one hand only for this purpose and leave him free to handle other instruments.

Other objects and advantages of the invention will be apparent from the following detail description when taken in connection with the accompanying drawings in which

Figure 1 is a perspective view looking upwardly at a patrol station unit embodying the invention, the cover or hood being removed;

Fig. 2 is a view partly in section and in elevation of the unit with the cover in position;

Fig. 3 is a transverse vertical section through the unit having the cover in position;

Figs. 4 to 10, inclusive, represent an exploded view of the various parts used in the construction of the unit;

Fig. 11 is a vertical sectional view partly in elevation to illustrate the manner in which the jack plug is inserted to complete the circuit connection; and

Fig. 12 is a perspective view looking at the

2

under side of the block carrying the spring pressed closure member normally closing off the opening for the jack plug when the jack plug is not inserted.

5 The device shown in the drawing as illustrative of a preferred embodiment of the invention comprises a housing having an intermediate frame member 5 formed into a plurality of sides 6, 7 and 8 with inturned flanges 9 and 10 defining the margins of a fourth side to which a terminal-carrying plate 11 is attached. Flanges 9 and 10 are tapped at 12 to receive screws 13 that pass through openings 14 in plate 11. End plates 15 and 16 serve as bottom and top plates, respectively, and are 15 formed in each instance with their sides turned as indicated broadly at 17, but with one of the sides designated 18 turned and formed with an offset 19. These end plates 15 and 16 are seated upon the ends of the frame member 5 and are 20 soldered or brazed thereto to form, if so desired, a sealed joint that will exclude dust, moisture, or other foreign matter. The offset portions or lugs 19 on each end plate will fit between the marginal flanges 9 and 10 and lie flush with the same 25 so as to form therewith a planar surface that will receive terminal carrying plate 11.

This latter plate 11 is formed from a single piece and has its side 20 turned so that when plate 11 is secured by screws 13 to flanges 9 and 30 10, this side 20 will lie approximately in the plane of side 8 and be coextensive therewith. A very simple form of perforated base 21 is provided adjacent side 20 by turning up the end of plate 11 and soldering or brazing the joint with side 20 35 as indicated at 22. Perforation 23 is adapted to receive the line wires adapted to connect to terminals 24 and 25 carried in openings 25' in the plate 11. These terminals 24 and 25 may be constructed in any suitable way as by insulation 40 bushings 26 carrying internally threaded metallic sleeves 27 having the usual wire connecting stud 28 at the inner end and the collar 29 at the opposite end between which and the head of screw 30 a collar 31 is disposed. To facilitate mounting 45 terminals 24 and 25, an insulation plate 32 may be disposed against the inside face of plate 11. If so desired, a gasket 33 may be used between plate 11 and the intermediate frame member 5 to secure a tight joint that will exclude dirt, 50 moisture and other foreign substances.

A mounting bracket 35 of elongated formation with a lower offset portion 36, that facilitates mounting thereof in any given location, may be employed to receive the frame member 5 as by 55 welding or the like. Bracket 35 need only be of a

width equal to frame member 5 and arranged to extend only part way therealong in the back thereof, if so desired. A protruding guide stud 34 may be pressed outwardly from back wall 8 so as to predetermine the positioning of bracket 35 against the outer face of back wall 8 with respect to the distance it will extend upwardly thereagainst and also to act as a guide for cover or hood 40 that is placed over the parts thus far described.

All these parts may be made by simple stamping operations and assembled in an extremely simple and quick manner.

Bottom plate 15 is provided with an opening 41 over which an insulation block 42 is placed and secured as by screws 43 to the plate 15. Block 42 may be provided with a raised portion 44 which extends into opening 41 and carries thereupon a terminal post or jack 45 having contacts 46 and 47, to which wires 48 and 49 connect to the terminal posts 24 and 25, respectively. Contacts 46 and 47 are insulated from each other by an insulation spacer 50, contact 46 being in current-conducting relation with the standard 51 of terminal jack 45 and contact 47 being in current-connecting relation with a spring contact finger 52. A jack plug 53 is adapted to be inserted into an opening 54 in insulation block 42 so that one of its terminals 55 is in electrical contact with a sleeve 56 fixedly secured in opening 54. Sleeve 56 is in electrical contact with standard 51 through its base 57, which is secured to insulation block 42 by screws 58. The other terminal 59 of jack 53 is electrically spaced from terminal 55 by an insulation washer 60 and is adapted to engage contact finger 52 as shown in Fig. 11. Thus a circuit connection is established to provide a communication connection with line wires that connect to terminals 24 and 25 and lead out through opening 23 in base 21 of plate 11. Jack plug 53 is part of the equipment carried by the patrol or field man and mere insertion of the same into opening 54 promptly establishes this communication connection by means of which he may converse with others at distant points.

The insertion of jack plug 53 in opening 54 is against the action of a spring pressed closure jaw or member 62 normally serving to lie over opening 54 to keep out dirt, moisture and rodents or insects that tend to enter for shelter and create temporary short circuits by lying across both terminals of the circuit. Closure member 62 may be pivotally carried upon bolt 63 receiving a nut 64 nested in opening 65. Bolt 63 is enlarged at 66 about which a coil spring 67 is disposed, one end of the coil spring being placed in a slot 68 formed in block 42; and the other end in a slot 69 formed in closure member 62.

It will be observed in Fig. 12 that closure member 62 is formed with a rounding but tapered face 70, forming a cam surface that terminates into an edge 71 overlying the opening 54. Spring 67 holds closure member 62 over opening 54, as previously stated, and the tension of the spring is sufficient to keep this edge 62 against a stop 72 carried upon block 42. Thus, opening 54 is kept closed. When jack plug 53 is adapted to be inserted, the field operator merely projects the head 59 thereof against this tapered face 70 of the closure 62, and, by the use of a slight side movement or pressure, the closure 62 will be cammed sidewise until opening 54 is cleared, this bringing closure 62 against a stop 73 carried by block 42 and uncovering the opening 54 to permit insertion of the jack plug, only one hand of the

operator being required for this purpose so as to leave him free also to handle other instruments.

Cover 40 is in the form of a hood adapted to be slidable over main frame 5 and terminal carrying plate 11 and to be seated, as shown in Fig. 2, so that the rear lower edge thereof rests upon the offset ledge 75 of bracket 35 and be locked in this position as indicated at 76. This cover 40 provides a compact enclosure for the entire structure and in effect a chamber 77 for terminals 24 and 25, as shown in Fig. 3, the only opening for this chamber 77 being opening 23 in base 21 through which the line wires are passed.

The interior of the main frame 5 may be completely sealed, and, if so desired, a gasket 78 may be used between bottom plate 15 and block 42.

Obviously, the construction described is rugged and completely weatherproof, although it may be subjected to outside use under the severest weather conditions. The structure is simple and inexpensive. Hence, its use may be more widespread and with little regard to loss. It is particularly adaptable for coastal protection, air fields, forestry and national park services, munitions and loading plants, highway patrols, docks, firing ranges, etc., or wherever it is desirable to establish a communication line and permit plugging in at various points. The frame members are simply formed and easily assembled. The line connections are easily made and the terminals therefor are simply mounted upon one side of the closed chamber, which side is removable to provide access to the closed chamber. It will be remembered that these simple features may novelly be used in structures using other terminal connections than a telephone jack, and hence, I do not desire to be necessarily limited to the use of a telephone jack within the closed chamber as long as the invention is employed.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. A terminal structure of the type described comprising a substantially closed chamber formed by side walls and end walls, one of said walls being removable, flanges along one side and the bottom of said removable wall forming in effect extensions of the bottom and the corresponding side wall of said closed chamber, terminals on said removable wall, a terminal mounting within said closed chamber for connection with said terminals on said removable wall, said bottom flange having a line wire opening through which line wires may extend upwardly for connection to said terminals, and a hood slidably mounted over said closed chamber and said flanges, the bottom end wall of said closed chamber being provided with an opening therein to provide access for a connection with said terminal mounting in said closed chamber.

2. A terminal structure of the type described comprising a substantially closed chamber formed by side walls and end walls, one of said walls being removable, flanges along one side and the bottom of said closed chamber forming substantially planar extensions of the bottom and the corresponding side wall of said closed chamber, terminals on said removable wall, a terminal

mounting within said closed chamber for connection with said terminals on said removable wall, said bottom flange having a line wire opening through which line wires may extend upwardly for connection to said terminals, and a hood slidably mounted over said closed chamber and said flanges, the bottom end wall of said closed chamber being provided with an opening therein to provide access for a connection with said terminal mounting in said closed chamber, a spring pressed closure member over said opening adapted to be swung to one side in making such connection, the bottom edge of the hood extending below the level of said bottom and closure member to protect the same.

3. A terminal structure of the type described comprising a substantially closed chamber formed by side walls and end walls, one of said walls being removable, flanges along one side and the bottom of said removable wall forming extensions substantially of the bottom and the corresponding side wall of said closed chamber, terminals on said removable wall, said bottom flange having a line wire opening through which line wires may extend upwardly for connection to said terminals, and a hood slidably mounted over said closed chamber and said flanges, the bottom end wall of said closed chamber being provided with an opening, an insulating block at the end wall over said opening, and a terminal jack carried by said block and extending within the closed chamber and having contacts connected with said terminals on said removable wall, said block having an opening therein through which a jack plug may be inserted for connection with said jack contacts.

4. A terminal structure of the type described comprising a substantially closed chamber formed by side walls and end walls, one of said walls being removable, flanges along one side and the bottom of said removable wall forming in effect extensions of the bottom and the corresponding side wall of said closed chamber, terminals on said removable wall, a terminal mounting within said closed chamber for connection with said terminals on said removable wall, said bottom flange having a line wire opening through which line wires may extend upwardly for connection to said terminals, a hood slidably mounted over said closed chamber and said flanges, the bottom end wall of said closed chamber being

provided with an opening therein, an insulating block disposed upon said end wall over said opening, said insulating block having an opening therein for access for a connection to said terminal mounting, means carried externally by said insulating block for normally closing said opening therein, and a mounting bracket over which said hood is slidably positioned, said bracket having an offset portion upon which said hood is seated, said seat and the lower edge of the hood being below the level of said insulating block and said closing means.

5. A terminal structure of the type described comprising a substantially closed chamber formed by side walls and end walls, one of said walls being removable, flanges along one side and the bottom of said removable wall forming in effect extensions of the bottom and the corresponding side wall of said closed chamber, terminals on said removable wall, a jack mounted within said closed chamber for connection with said terminals on said removable wall, said bottom flange having a line wire opening through which line wires may extend upwardly for connection to said terminals, and a hood slidably mounted over said closed chamber and said flanges, the bottom end wall of said closed chamber being provided with an opening therein to provide access for a jack plug for insertion in said jack in said closed chamber.
